Primary Examiner — Kelley A Donnelly(74) *Attorney, Agent, or Firm* — Lowe Graham Jones PLLC(57) **CLAIM**

I claim the ornamental design for a tray with divider, as shown and described.

DESCRIPTION

FIG. 1 is a top perspective view of a tray with divider, showing my new design.

FIG. 2 is a bottom perspective view of the tray with divider.

FIG. 3 is a front elevational view of the tray with divider, the rear view being a mirror image.

FIG. 4 is a right side elevational view of the tray with divider, the left side view being a mirror image.

FIG. 5 is a top plan view of the tray with divider.

FIG. 6 is a bottom plan view of the tray with divider.

FIG. 7 is a top perspective exploded view of the tray with divider.

FIG. 8 is a front elevational exploded view of the tray with divider, the rear elevational exploded view being a mirror image; and,

FIG. 9 is a right side elevational exploded view of the tray with divider, the left side elevational exploded view being a mirror image.
